(57) **CLAIM**

The ornamental design for a bird toy, as shown and described.

DESCRIPTION

FIG. 1 is a perspective view of a bird toy showing my new design;

FIG. 2 is a front elevation view thereof, the rear elevation view being identical;

FIG. 3 is a left side elevation view thereof, the right side elevation view being identical;

FIG. 4 is a top plan view thereof; and,

FIG. 5 is a bottom plan view thereof.

The broken lines showing the hanging chain in FIGS. 1-3, the different rotatable and movable shapes in FIGS. 1 and 2 and the chain hole in FIGS. 1 and 4 are for illustrative purposes only and form no part of the claimed design.
